(57) CLAIM

The ornamental design for decorative features for a shoe, substantially as shown and described.

DESCRIPTION

FIG. 1 is a left side view of decorative features for a shoe showing my new design; and,

FIG. 2 is a right side view thereof.

The broken lines depicting a shoe are for environmental purposes only and form no part of the design claimed.

1 Claim, 2 Drawing SheetsFIG.1
